CLAIM

The ornamental design for a vial adapter, as shown and described.

DESCRIPTION

FIG. 1 is a front top perspective view of a first embodiment of a vial adapter showing the new design;

FIG. 2 is a rear top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof.

FIG. 9 is a front top perspective view of a second embodiment of a vial adapter showing the new design;

FIG. 10 is a rear top perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines shown in the figures are for the purpose of illustrating portions of the vial adapter and form no part of the claimed design.
